UNITED STATES PATENT OFFICE.

JOHN A. BRUBAKER, OF TOLEDO, OHIO, ASSIGNOR TO THE HAUGHTON ELEVATOR AND MACHINE COMPANY, OF TOLEDO, OHIO, A CORPORATION OF OHIO.

ELEVATOR INTERLOCK.

Application filed July 20, 1927. Serial No. 207,135.

This invention relates to an elevator interlock for controlling the operation of the car, so that none of the landing doors can be opened in the usual manner unless the car is 5 opposite the same, and the car cannot start up or down until the door has been closed and locked. The interlock is equally adaptable for use on either a sliding or a swinging door.

In the operation of elevators equipped 10 with interlocks having rotating tumblers, as heretofore commonly constructed, the functioning of the interlock depends upon a small spring, and if this spring is broken or fails to act as intended, the door can be opened when 15 the car is not there. Moreover, with the interlock functioning normally, if the car stopped below the floor, the door may be opened manually from the inside of the car, without locking the car against starting. 20 Such conditions are very dangerous, and it is with the object of correcting same that the present invention has been perfected.

The objects and advantages of the invention 25 will be more specifically explained in connection with the accompanying drawing which illustrates one embodiment thereof.

In the drawing:

Figure 1 represents the invention in elevation as viewed from the inside of the shaft, 30 the cover of the lock casing being removed.

Fig. 2 is a sectional view taken on the line 2—2 of Fig. 1.

In its present embodiment, the invention is shown in connection with a sliding door 5 35 having a horizontal bar 6 secured thereto and projecting beyond the edge of the door where it terminates in a hook 7. A lock casing 8 is mounted on the side of the elevator shaft and spaced from the door jamb 9 a sufficient distance so that the interlocking 40 mechanism will be clear of the corner of the car.

The hook 7, as the door closes, is adapted to engage in a recess 10 formed in a tumbler 11 45 mounted on a stud 12 extending from the bottom of the casing 8. The tumbler is held against movement lengthwise of the stud 12 by a pin 13 or the like. A latch 14 is pivotally mounted on a spindle 15 secured in the lower part of the casing 8 and its upper end 16 is adapted to cooperate with a projection 17 50 on the tumbler 11 to lock the latter against rotation, thereby locking the door 5 in closed position.

55 The center of gravity of the latch 14 is at

one side of the spindle 15 so that the latch may be held in locking position by gravity alone. It is preferred, however, to provide a coil spring 18 which also tends to hold the latch in locking position. This spring is 60 mounted on a stem 19 which projects from the back of the casing 8 through an ear 20 formed on the latch 14 and the stem 19 is provided at its outer end with a head 21 against which the spring 18 is seated.

When the elevator car stops in a position 65 opposite the doorway, the latch 14 is adapted to be withdrawn from behind projection 17 of the tumbler so as to permit the door to open. To effect this operation an angular 70 arm 22 is secured to the lower end of the latch 14 and carries a roller 23 at its lower end which is engageable by a retiring cam 24 carried by the elevator car 25. The arm 22 is mounted on a pivot bolt 26 and has a pin and 75 slot connection 27 with the lower end of the latch 14 so that it may be adjusted to the position of the cam.

The interlock device may be used in connection with a retiring cam of any suitable 80 construction. By way of illustration, the cam 24 is shown as carried by links 28 pivoted to the side of the car 25. A solenoid core 29 is pivotally connected to the upper end of the cam 24 and when the coil 30 is energized 85 the cam 24 is held in retired position so as not to engage the roller 23. When the coil 30 is de-energized, however, the cam 24 drops by gravity until it is stopped by a lug 31. The coil 30 is in a relay circuit 32 which must be 90 energized before the car can be started and as soon as the coil 30 is energized the cam 24 is raised to release the latch 14 and permit it to move into locking position.

The circuit for operating the car is through 95 wires 33 and 34 which are connected respectively to bars 35 and 36 of conductive material mounted on an insulating base 37 secured to the back of the casing 8. An insulating bar 38 is secured to the latch 14 and carries at its end a contact 39 which is electrically connected to the bar 35 by a flexible conductor 40. As soon as the latch 14 is released and permitted to move into locking position under the influence of gravity or the spring 100 18, the contact 39 engages bar 36 and a circuit is established from the wire 33 through bar 35, conductor 40, contact 39, bar 36, to the lead wire 34. Not until the door is locked 105 and the contact 39 closed, can the circuit 110

through the car operating motor be established.

The upper portion of the latch 14 is guided between abutments 41 which are secured to the casing 8 so that no matter how much pressure is exerted against the door to open it when it is locked, the latch cannot be forced out of its perpendicular relation to the pivot pin 15. Studs 42 extend outwardly from the members 41 and constitute seats against which the cover 43 of the casing may be secured.

As long as the car is moving the coil 30 is energized and holds the cam 24 in retired position so that the latch 14 is in position to lock the door. The coil 30 will be de-energized and permit the cam 24 to drop only after the current which operates the car is turned off. If the car stops in proper position opposite the door, the cam 24, as it comes forward, strikes the roller 23 and moves the latch 14 to unlock the door, at the same time opening the circuit through the contact 39 and making it impossible to run the car again until the circuit is closed.

When the door is opened, the hook 7 rotates the tumbler 11 and the portion 44 of the tumbler passes underneath the end 16 of the latch and prevents the latter from being moved to close the circuit through the car operating motor until the tumbler 11 has been returned by the closing of the door. When the door is opened the weight of the larger portion 44 of the tumbler holds it in position to prevent the contact 39 from being closed and in position to receive the hook 7 as the door is closed again.

It will be seen, therefore, that the car cannot leave a floor until the door is closed and mechanically locked. It is difficult to tamper with the lock or to put it out of commission since the tumbler is difficult to roll except by the means provided for the purpose and will always drop by gravity to unlocked position if not held. The locking device may be easily installed since it does not require any close or accurate seating.

If any person, by unauthorized tampering with the lock, should succeed in rolling the tumbler to locking position, while the door is open, and in holding the tumbler in that position while someone pushes the button and starts the car, the weight of the portion 44 will nevertheless, as soon as the car again stops at that floor, cause the position of the tumbler to be rectified so that the normal operation of the lock will be restored.

It will be obvious that the lock may be used either on swinging doors or sliding doors. It may be reversed for either right hand or left hand operation by reversing the position of the tumbler 11 on the stud 12. Of course, a suitable key may be provided for unlocking the door in case of emergency. While the spring 18 is provided to assist in holding the latch 14 in locking position, the

latch is so balanced that if the spring should break or become lost the latch will still be operated by gravity.

While I have shown and described in considerable detail one specific embodiment of the invention it is to be understood that this is merely for the purpose of illustration and that various modifications may be made therein without departing from the scope of the invention as defined in the claims. 75

What I claim is:

1. In an elevator interlock, the combination with a bar adapted to be attached to a door and having a hook thereon, of a casing with a tumbler rotatably mounted therein and having a recess for receiving said hook, a projection on said tumbler, a latch mounted so as to be movable by gravity into position behind said projection to lock the door when closed, and gravity actuated means operable to withdraw said latch out of the path of said projection only when the car is opposite the door. 80

2. In an elevator interlock, the combination with a bar adapted to be attached to a door so as to project therefrom, said bar terminating in a hook, of a casing with a tumbler rotatably mounted therein and having a recess for receiving said hook, a projection on said tumbler, a latch, spring means 95 acting upon the latch to move the same into position behind the projection to lock the door when closed, said latch being so mounted that it is movable into locking position by gravity if the spring means fails, an operating arm connected with said latch, a retiring cam, and means operable to cause said cam, in connection with said operating arm, to withdraw said latch out of the path of said projection only when the car is opposite the 100 door. 105

3. In an elevator interlock, the combination with a bar adapted to be attached to a door so as to project therefrom, said bar terminating in a hook, of a fixed casing, a tumbler rotatably mounted therein and having a recess in its periphery adapted to receive said hook, means positively preventing movement of said tumbler lengthwise of its axis, a radial projection on said tumbler, a latch having an end movable by gravity transversely into the path of said projection behind the same to lock the tumbler and thereby lock the door when closed, an operating arm connected with said latch, a retiring cam, and means operable to cause said cam, in connection with said operating arm, to withdraw said latch out of the path of said projection only when the car is opposite the door. 110 115 120

4. In an elevator interlock, the combination with a bar adapted to be secured to a door so as to project therefrom, said bar terminating in a hook, of a fixed casing with a tumbler rotatably mounted therein and having a peripheral recess for receiving said 125 130

hook, means positively preventing movement of said tumbler lengthwise of its axis, a radial projection on said tumbler, a latch, spring means acting upon the latch to move 5 the same into position behind said projection to lock the tumbler and thereby lock the door when closed, said latch being so mounted that it is movable into locking position by gravity if the spring means fails, an operating arm connected with said latch, a retarding cam, and means operable to cause said cam, in connection with said operating arm, to withdraw said latch out of the path of said projection only when the car is opposite the 10 door.

5. In an elevator interlock, the combination with a door having a bar projecting therefrom and terminating in a hook, of a casing with a tumbler rotatably mounted 20 therein and having a recess for receiving said hook when the door is closed, a latch engageable with said tumbler to lock the door closed, an insulating block mounted in said casing, two electrically conductive bars 25 mounted on said block, means for connecting said bars respectively to the lead wires of an electric circuit, a contact carried by said latch and insulated therefrom, said contact being electrically connected to one of 30 said bars and in position to establish an electrical connection with the other bar only when said latch is in locking relation to said tumbler.

6. In an elevator interlock, the combination 35 with a door, of a fixed casing mounted adjacent the doorway, a latch projecting into said casing, a rotatable tumbler with which the latch normally cooperates to lock the door when closed, means for moving the latch to 40 unlocking position when the car stops opposite the same, an insulating block mounted within said casing, two electrically conductive bars mounted on said block, means for connecting said bars respectively to the lead 45 wires of an electric circuit, a contact carried by said latch and insulated therefrom, said contact being electrically connected to one of said bars and in position to establish an electrical connection with the other bar only 50 when said latch is in locking relation to said tumbler, whereby to prevent starting the elevator car unless said latch is in locking position.

7. In an elevator interlock, the combination 55 with a door having a bar projecting therefrom and terminating in a hook, of a casing with a tumbler rotatably mounted therein and having a recess for receiving said hook when the door is closed, a latch engageable with said tumbler to lock the door closed, a circuit for controlling the operation of the elevator car and including a contact carried by said latch, said contact being in position to close said circuit only when 60 the latch is in locking relation to the tumbler.

8. In an elevator interlock, the combination with a door, of a fixed casing mounted adjacent the doorway, a latch associated with said casing, a rotatable tumbler within the casing with which the latch normally cooperates to lock the door when closed, means for moving the latch to unlocking position when the car stops opposite the same, a circuit for controlling the operation of the elevator car and including a contact carried by 70 said latch, said contact being in position to close said circuit only when the latch is in locking relation to the tumbler, thereby making it impossible to start the elevator car except when the door is closed and locked. 80

9. In an elevator interlock, the combination with a bar adapted to be attached to a door and having a hook thereon, of a casing with a tumbler having a notch normally in position to receive said hook, a projection on 85 said tumbler, a latch normally engageable behind said projection to lock the door when closed, and means rendered operable by opening the car operating circuit, only when the car is opposite the door, to withdraw said 90 latch out of the path of said projection and to always maintain it in that position until the car operating circuit is again closed.

10. In an elevator interlock, the combination with a door, of a bar projecting therefrom in the direction of the jamb toward which the door moves in closing, said bar terminating in a hook, a casing having an opening which the hook enters as the door closes, a rotatably mounted tumbler within 95 the casing and having a notch normally in position to receive the hook as it enters through said opening, so that a rotary movement is imparted to the tumbler, means operable to lock said tumbler with the door 100 closed, and means operable to start the car including an electric circuit and a switch which is closed by said tumbler locking means until the latter is in locking position.

11. In an elevator interlock, the combination with a bar adapted to be attached to a door and having a hook thereon, of a casing with a tumbler mounted therein and having a notch normally in position to receive said hook, a projection on said tumbler, a latch 110 normally engageable behind said projection to lock the door when closed, and means controlled by the car operating circuit and rendered operable by opening said circuit, only when the car is opposite the door, to withdraw said latch out of the path of said projection and to maintain it in that position until the car operating circuit is again closed.

12. In an elevator interlock, the combination with a bar adapted to be attached to a 125 door and having a hook thereon, of a casing with a tumbler mounted therein and having a notch normally in position to receive said hook, a projection on said tumbler, a latch normally engageable behind said projection 130

- to lock the door when closed, an operating arm connected with said latch, a retiring cam, and means rendered operable by opening the car operating circuit, only when the car is opposite the door, to cause said cam, in connection with said operating arm, to withdraw said latch out of the path of said projection and to maintain it in that position until the car operating circuit is again closed.
13. In an elevator interlock, the combination with a hatchway door, of a casing with a tumbler rotatably mounted therein, means associated with the tumbler for locking the door when the latter is closed and the tumbler is in locking position, a car operating circuit, means normally operable, only when the car is opposite the door and the current shut off, to release the tumbler to permit the door to be opened, said car operating circuit including contacts which are normally open when the door is unlocked, means associated with the tumbler and tending to move it to unlocking position or to restore it to that position in the event it is tampered with, and means operable by the door, in closing, to move the tumbler to locking position in opposition to such tendency.
14. In an elevator interlock, the combination with a hatchway door, of a casing with a tumbler rotatably mounted therein, means associated with the tumbler for locking the door closed except when the car is opposite the door, a car operating circuit including contacts which can be closed only when the tumbler is in locking position, and means associated with the tumbler, independent of the door, and tending to hold the tumbler in unlocking position, thereby holding the car op- erating circuit open, or to restore it to that position in the event it is tampered with. 40
15. In an elevator interlock, the combination with a fastening member adapted to be attached to a door, of a casing with a tumbler rotatably mounted therein, said fastening means being engageable with the tumbler to 45 rotate the latter from unlocking to locking position as the door is closed, means associated with the tumbler and the fastening member for locking the door when the tumbler is in locking position, means, operable 50 only when the door is locked, to start the car, and means associated with the tumbler and operable to move said tumbler to unlocking position, or normally to maintain it in such position, unless it is moved out of such position by said fastening means.
16. In an interlock, a tumbler rotatable to locking or unlocking position, fastening means cooperating with said tumbler to rotate the same from one of said positions to the 60 other, means to lock said tumbler in locking position, and means, independent of said fastening means and locking means, tending to rotate the tumbler to unlocking position.
17. In an interlock, a tumbler rotatable to 65 locking or unlocking position, fastening means cooperating with said tumbler to rotate the same from one of said positions to the other, and means to lock said tumbler in locking position, said tumbler being so weighted 70 that it tends to rotate to unlocking position independently of the operation of the fastening means and locking means.

In testimony whereof I have hereunto signed my name to this specification.

JOHN A. BRUBAKER.
